N. Y., a corporation of New York

Original application December 21, 1937, Serial No.
180,999. Divided and this application May 9,
1938, Serial No. 206,957

13 Claims. (CL 93—36)

The present invention relates to the method of constructing display receptacles or containers intended for use in displaying and marketing merchandise of different classes, such, for example, as articles of wear, novelties of different kinds, food products, and other forms of merchandise.

One object of the invention is to provide an improved method of constructing receptacles or containers of the class described of sheet material and in a manner to render the receptacles strong and durable and capable of protecting the contents thereof during handling and shipment of the receptacles.

15 A further object of the invention is to provide an improved method of constructing a unitary section of an article display receptacle, such for example as a cover section of flexible sheets of material, which facilitates forming and uniting the several sheets of the section in an effective and economical manner.

25 A further object of the invention is to provide an improved method of constructing one or more sections of an article display receptacle of a plurality of blanks and by which method the blanks can be readily assembled, formed, and connected by suitable means, such, for example, as adhesive material and in a manner to effect a saving in the time required to complete the sections and in the cost of constructing the same.

30 A further object of the invention is to provide a novel and improved method of constructing a window section for telescopic engagement with another section of an article display receptacle and by which method pre-cut body, cover, and transparent sheets can readily be assembled in superimposed relation and folded and united to complete the section with a minimum number of operations.

40 To these and other ends the invention resides in certain improvements and combinations of parts, all as will be hereinafter more fully described, the novel features being pointed out in the claims at the end of the specification.

45 In the drawings:

Fig. 1 is a perspective view of a box or receptacle disclosing one embodiment of the invention;

50 Fig. 2 is a perspective view of the cover shown removed from the receptacle with portions broken away to better illustrate the construction of the same;

55 Fig. 3 is a perspective view of the bottom or body section of the receptacle;

Fig. 4 is a transverse section on the line 4—4 of Fig 2;

Fig. 5 is a transverse section on line 5—5 of Fig. 2;

Fig. 6 is a longitudinal section on line 6—6 of Fig. 1;

Fig. 7 is a transverse section through one of the side walls of the cover, drawn to an enlarged scale and showing the method of connecting the transparent and outer sheet of the cover with the side wall of the supporting frame therefor;

Fig. 8 is a perspective view of the supporting frame of the top or cover section of the receptacle;

Fig. 9 is a view illustrating the blank corresponding to the outer cover sheet of the receptacle;

Fig. 10 is a view of the transparent window sheet which constitutes a part of the top and side walls of the cover;

Fig. 11 is a view of the blank from which the frame of the cover section of the box is formed;

Fig. 12 is a perspective view showing the outer sheet of the cover, the transparent sheet thereon and the frame of the cover section of the receptacle assembled preparatory to operating upon the same to complete the cover;

Fig. 13 is a perspective view of a display receptacle embodying a modified form of the invention;

Fig. 14 is a perspective view of the cover section of the receptacle shown in Fig. 13;

Fig. 15 is a perspective view of the bottom or body section of the receptacle shown in Fig. 13;

Fig. 16 is a transverse section on line 16—16 of Fig. 14;

Fig. 17 is a view illustrating the blank corresponding to the wrapper or cover sheet for the frame of the cover section of the receptacle;

Fig. 18 is a view of a transparent window sheet for closing the openings in the frame of the cover section through which the articles are rendered visible, and

Fig. 19 is a view of the blank from which the frame structure of the cover section shown in Fig. 14 is formed.

The same reference numerals throughout the several views indicate the same parts.

The present application constitutes a division of my copending application Serial No. 180,999, filed December 21, 1937, for Display receptacle and method of making same. This application relates to a method or methods of forming display receptacles for different articles of merchandise and embodies generally, the use of sev-

eral blanks cut to predetermined shapes and sizes and folded and connected to complete one section of a container or receptacle designed to have telescoping sections, one of which may be termed 5 a body section and the other a cover section. The body section is adapted to receive the cover section and may be formed in any preferred manner. However, the cover section is preferably formed of three blanks comprising an inner 10 or frame forming sheet, an outer or cover sheet and a transparent window forming sheet interposed between said inner and outer sheets.

The cover section may be formed in several 15 different ways, one of which, for example, comprises scoring and folding the inner sheet or blank to form a frame structure having side and end walls, positioning said frame structure upon the cover and transparent sheets and folding the sides of the transparent and cover sheets and 20 the ends of the latter into position upon the walls of the frame structure and securing them thereon.

Another method of forming the cover section 25 is to superimpose the inner and outer sheets, while in blank form, one upon another with the transparent sheet therebetween and then folding the sheets to form a cover section having top, side, and end walls and in which structure the transparent sheet forms a portion of the top and side walls to provide a window through which to 30 view the contents of the receptacle.

Referring to the drawings 10 designates an article display receptacle constructed in accordance with my improved method, said receptacle comprising separable telescoping bottom and top 35 or body and cover sections 11 and 12, respectively, the cover section 12 being shown in Fig. 2, and the body section in Fig. 3. The body section 11 comprises an elongated box-like frame which may be formed of any suitable material, such, for 40 example, as cardboard or the like, and includes bottom, end and side walls 13, 14, and 15, respectively. The side walls are cut away for a portion of their length to form openings therein, as indicated in Fig. 3, whereby to render the article 45 or articles contained in the receptacle visible both through the side and top walls of the receptacle when the cover is applied to the bottom section as shown in Fig. 1.

The cover or top section of the receptacle is 50 formed of three blanks or sheets of material, designated generally by the reference numerals 16, 17, and 18, in Figs. 9, 10, and 11 of the drawings respectively, said sheets being cut to the desired shapes and sizes to form the blanks necessary 55 to the construction of the cover section of the receptacle. The blank 16 constitutes the outer or finishing sheet of the cover section, and 17 the transparent window forming sheet, while 18 constitutes the sheet from which the frame or supporting structure of the cover section is formed, as shown in Fig. 8, the frame being also designated by the reference numeral 18 and formed of relatively stiff or heavy cardboard, or other suitable material.

60 The blank 16 is formed of paper or other suitable material and the blank 17 of transparent sheet material such, for example, as "Kodapak," "Cellophane," or other suitable transparent material. The blank 18 from which the frame is formed, is cut to provide an opening 20 which is surrounded by the side and transverse portions 21 and 22 of the blank, respectively, said transverse portions having extensions 23 thereon as shown in Fig. 11. The blank is scored at 24 and 75 25 to permit the side and end portions 21 and 23

to be folded inwardly to form the box-like frame shown in Fig. 8, the side and end walls of which are connected by the corner strips 26 which are secured upon said walls by suitable means such, for example, as glue or other adhesive material 5 whereby to complete the frame.

By constructing the frame 18 in the manner shown and described the side walls thereof are reduced in depth for the greater portion of their length, with the result that the cover section of 10 the receptacle will have a relatively long and deep opening through which to view the contents of the receptacle.

The opening 20a of the blank 16 corresponds substantially in shape and size to the opening 20 15 of the blank 18. The side portions 21b of the blank 16 correspond to the side portions 21 of the frame 18, while the transverse portions 22b of said blank correspond to the portions 22 of the frame. Likewise the end portions 23b of the 20 blank correspond to the ends 23 of the frame.

The end portions 26a of the blank 16, when forming and applying the latter to the frame of Fig. 8, will be folded around the end walls 22 of the frame and down upon the strips 26 thereof, it 25 being understood that the inner face of the sheet forming the blank 16 will have adhesive material such, for example, as glue applied thereto as indicated by the stippling shown in Fig. 9, before applying the sheet to the frame.

In order that the operator may accurately 30 apply the transparent sheet 17 to the blank 16 the latter is provided with the angular shaped markings 17a which correspond to the corner portions of the transparent sheet and which facilitate the proper positioning of said sheet upon the blank, in which position it will be held by the glue on the latter, said markings being applied to the sheet by printing them thereon or otherwise as desired.

The transparent sheet is of a length somewhat 40 less than that of the frame 18 whereby when the latter is positioned on the blank 16, as shown in Fig. 12, its ends will extend beyond the ends of said sheet and, in overlying engagement with the blank, or in other words will extend to the base lines 23c of the extensions 23b, in which position said ends will be held in contact with the blank by the adhesive material thereon.

One method of assembling the parts forming 50 the cover section of the receptacle comprises first positioning the transparent sheet 17 on the blank 16 with the corners of the sheet in substantial registry with the markings 17a, at which time the opening 20a of the blank will be closed by 55 said sheet. The next step is that of positioning the frame 18 in overlying relation upon the transparent sheet 17 and with its ends on the portions of the blank lying between the ends of said sheet and the base lines 23c of the extensions 60 23b, or in other words as shown in Fig. 12. When the blanks 16 and 17 and the frame 18 are assembled as shown in Fig. 12 they are ready for the forming operation, which may be effected by any preferred means such, for example, as 65 suitable male and female dies within the latter of which the assembly shown in Fig. 12 will be forced by the former to cause the marginal portions of the blanks 16 and 17 or those which extend beyond the edges of the frame 18 to be 70 folded into contact with the outer faces of the walls of the frame. In this operation the end portions 26a of the blank will be folded into engagement with the portions of the strips 26 which overlie the end walls of the frame 18, after 75

which the end portions 23b of the blank will be folded into engagement with said end walls, suitable means being also employed to fold the side and end edges of the portions 21b and 23b, respectively, of the blank 16 down upon the inner faces of the side and end walls of the frame 18, upon which said folded edges will be secured by the adhesive material previously applied to said edges, as indicated by the stippling of Fig. 9 and as shown at 16a in Fig. 7.

Another method of forming the cover section of the receptacle is to superimpose the cover and frame forming blanks 16 and 18 in proper relation one relative to another with the window forming transparent sheet 17 therebetween, adhesive material having previously been applied to one of the blanks, preferably the blank 16, to secure the blanks one upon another. Upon thus assembling the blanks the side walls thereof will be folded along the lines of scoring 24 of the blank 18 to form a channel-shaped section and at about the same time the ends 23 of the blank 18 will be folded along the lines of scoring 25, following which the portions 26a of the blank 16 will be folded into position upon the ends 23 of the blank 18. When these operations have been completed the marginal portions of the side and end walls of the blank 16 will be folded downwardly upon the inner faces of the side and end walls of the blank 18 upon which they will be secured by the adhesive material applied to said marginal portions. With this method the corner strips 26 shown in Fig. 12 may be applied or omitted as desired, but if employed they can be applied before folding the portions 26a of the blank 16 into position on the ends 23 of the blank 18. It will be understood that the method just described can be performed by hand if desired, or by suitable machine operated parts, constructed and timed to fold the different portions of the blanks one relative to another in the manner described.

In the modification shown in Fig. 13, the receptacle 28 corresponds generally to that shown in Fig. 1, the cover section of the receptacle being shown at 29 in Fig. 14 and the body section at 30 in Fig. 15. The method of constructing the cover section 29 of the receptacle 28 is substantially the same as that previously described in connection with the cover section 12 of the receptacle 10 of Fig. 1. The body section of the receptacle 28 is preferably formed of stiff cardboard material and includes bottom, side, and end walls 31, 32, and 33, respectively, said side and end walls being cut away to provide openings therein and to afford rigid upstanding corner posts 34 which serve to support the cover section when the sections are in assembled relation, as shown in Fig. 13.

The cover section 29 embodies a substantially rigid frame structure 35, also formed of stiff cardboard or other suitable material, and includes the side and end walls 36 and 37, respectively, connected by suitable corner strips 38, as shown in Fig. 14. The side and end walls of the frame structure 35 are cut away to provide openings therein corresponding to the openings in the side and end walls of the body section. The openings in the side and end walls of the cover frame structure terminate short of the ends of said walls to provide upstanding corner posts 39 which include the connected upstanding ends of the side and end walls of the receptacle and the inwardly extending horizontal top wall portions 39a thereof which are adapted to rest on the

angular corner posts 34 of the body section 30 when the sections are in assembled relation, as shown in Fig. 13. The frame structure 35 of the cover section 29 is formed from the blank 35, shown in Fig. 19, which is cut to provide a relatively large opening in the top wall of said frame structure and which includes the vertical openings in the side and end walls of the frame structure when the cover section is completed, as shown in Fig. 14, said openings affording visibility of the contents of the receptacle to a relatively high degree.

The corresponding portions of the blank and frame structure 35 are designated by the same reference numerals as shown in Figs. 14 and 19. The portions 39a of said frame structure constitute, in each case, a portion of one of the corner posts of said frame structure. The blank 35 is scored on the lines 36c and 37c to permit its side and end walls to be folded into position to receive the connecting corner strips 38, as shown in Fig. 14.

The opening in the top, side, and end walls of the cover frame structure is closed by a transparent sheet 40 formed, for example, of cellulose acetate, or other suitable transparent material. The blank corresponding to the transparent sheet 40 is shown in Fig. 18, the side and end portions 36b and 37b of which serve to close the side and end openings in the frame structure 35 of the cover section, the remaining or central portion of the sheet constituting the top wall of the cover section, other than the inwardly extending corner portions 39a of said frame structure.

The frame structure 35 of the cover section 35 is provided with a cover sheet 41 of paper or other suitable material, which is formed from the blank 41 shown in Fig. 17. The opening in the blank 41 corresponds to the opening in the blank 35 and the side and end wall portions 36d and 40 37d correspond to the side and end portions 36 and 37 of the frame forming blank 35, while the portions 39d correspond to the portions 39a of the blank 35.

The method of forming the cover section 35 is similar to that employed in the forming of the cover section 12 of Fig. 2 of the drawings. In other words, the frame 35 is formed by folding the side and end wall portions of the blank 35 and uniting said portions by the corner strips 38. Furthermore the transparent window sheet 40 will be placed upon the inner face of the cover sheet 41 and united therewith by the adhesive material applied thereto, which is indicated by the stippling in Fig. 17. The frame 35 will then be superimposed upon the transparent sheet 40 with the portions 39a of the cover section in substantial alinement with the portions 39d of the cover sheet. The assembling of the blanks and said frame in this manner can, if preferred, be readily effected while advancing the same, as by means of a conveyor or other moving part for delivering the assembly to the forming dies or other means for folding the marginal portions of the transparent and cover sheets into proper position upon the frame 35, which includes folding of the edges of the cover sheet inwardly of the side and end walls of the frame 35, as shown at 36d in Fig. 16, in which position said edges are secured, by the adhesive material thereon, to the inner faces of said side and end walls.

It will be understood that the blanks 35, 40, and 41 of the modified cover section 29 can be assembled in superimposed relation while in flat 75

condition and folded and connected in a manner similar to that outlined above in the second method described in connection with the blanks shown in Figs. 9, 10, and 11. It will be further understood that in constructing the cover section 29 by said second mentioned method that the corner strips 38 may be omitted if desired.

The principal difference between the cover sections 12 and 29 is that the ends of the transparent sheet of the latter are extended to close the openings in the end walls of the section which serve to increase the visibility of the contents of the receptacles. However, the fact that the end walls are provided with openings and that the transparent sheet is extended to close the same does not prevent forming of the section by either of the methods described above.

The article display receptacles constructed in accordance with the methods described herein each has a relatively large window opening through which to view the articles contained therein, notwithstanding which fact the receptacles, in each case, are of strong and more or less rigid construction and capable of maintaining their shape and of protecting the articles contained therein during shipment or handling from time to time. This is true for the reason that each of the receptacles is formed of substantially rigid telescoping frame-like sections affording a double wall construction, the strength and rigidity of which is sufficient to prevent buckling or collapse of the receptacles when subjected to rough handling or to pressure exerted thereon when the receptacles are stacked in large numbers either when empty or supplied with the articles to be shipped therein.

In the receptacle shown in Fig. 1, for example, the upstanding end portions of the cover and body sections are each of substantially rigid construction, the said end portions being tied together by the reduced side wall portions of the sections and braced by the bottom wall of the body section, which in turn is strengthened and braced at points between the ends of said bottom wall by the upstanding web portions thereon.

Furthermore, in the modified receptacle shown in Fig. 13, the upstanding corner posts 34 of the body section and the correspondingly shaped corner posts 39 of the cover section are of substantially rigid construction and cooperate to increase the strength and rigidity of the receptacle, as do the reduced portions of the side and end walls of the sections and the bottom wall of the body section.

Although several methods of constructing the cover sections of the receptacle have been described, it will be understood that the same may be varied to a certain extent or within certain limits without departing from the spirit of the invention.

I claim:

1. The method of forming a cover section of an article display receptacle, comprising superimposing a transparent sheet upon a cover sheet having an opening therein to close said opening, superimposing a substantially rigid frame structure having a window opening on said cover sheet in spaced relation to the marginal portions thereof and with said openings in substantial alinement one with another, folding the marginal portions of said cover sheet into position upon a plurality of the walls of said frame structure and in such manner that the transparent sheet extends on two sides of the section, and uniting the marginal portions of the cover sheet with a

plurality of the walls of said frame structure by means of adhesive material.

2. The method of forming a unitary section of a display receptacle from apertured inner and outer sheets and a transparent sheet, the outer sheet being greater in size than the inner sheet, comprising positioning the apertured sheets in overlying relation one relative to another with the marginal portions of the outer sheet extending beyond the marginal portions of the inner sheet and with the transparent sheet between the inner and outer sheets in position to close the apertures, folding said sheets and uniting them by the use of adhesive material to form a substantially rectangular section having side, end, 15 and top walls with the transparent sheet forming portions of said top and side walls to provide a window for said section, and folding the marginal portions of the outer sheet downwardly within the section upon the walls of the inner sheet and 20 uniting said marginal portions with said walls by the use of adhesive material, said sheets being folded so that the transparent sheet extends on two sides of the section and has a rounded corner.

3. The method of forming a display box which comprises forming a bottom section with a base and upstanding side walls, part of at least one of said side walls being lower than other of said side walls to constitute a cutaway part, forming 30 a cover section with a top wall and depending side walls adapted to telescope down over the side walls of the bottom section, said cover section being also provided with an opening in its top wall and an opening in at least one of its side walls formed as a continuation of the opening in the top wall, covering said openings with a continuous sheet of transparent material, and superimposing the cover section on the bottom section so that the opening in the side wall of 40 the cover section is in registry with the cutaway part of the bottom section whereby the contents of the box may be viewed through a continuous transparent opening either from the top or a side of the box.

4. The method of forming a display box which comprises forming a bottom section with a base and upstanding side walls, part of at least one of said side walls being lower than other of said side walls to constitute a cutaway part, forming a 50 cover section with a top wall and depending side walls substantially as deep as the side walls of the bottom section and adapted to telescope down over the side walls of the bottom section so that the top wall of the cover section rests upon the upper edges of certain of the side walls of the bottom section when the box is assembled, said cover section being also provided with an opening in its top wall and an opening in at least one of its side walls formed as a continuation of 55 the opening in the top wall, covering said openings with a continuous sheet of transparent material, and superimposing the cover section on the bottom section so that the opening in the side wall of the cover section is in registry with the cutaway part of the bottom section whereby the contents of the box may be viewed through a continuous transparent opening either from the top or a side of the box.

5. The method of forming a cover section of an article display receptacle comprising superimposing a transparent sheet and an opaque sheet with respect to each other, the opaque sheet having an opening therein and the transparent sheet closing said opening, superimposing with respect to 75

each other a substantially rigid box-like frame structure having an opening with the opening in the frame structure substantially in alignment with the opening in the opaque sheet, and 5 folding the marginal portions of at least one of said sheets into engagement with a plurality of the walls of said frame structure, and securing said folded portions upon said walls, said sheets being folded so that the transparent sheet extends 10 on two sides of the section.

6. The method of forming a cover section of an article display receptacle, comprising superimposing a transparent sheet upon a cover sheet having an opening therein to close said opening,

15 superimposing upon one of said sheets a substantially rigid frame structure having window openings in two different sides of said frame structure, with the opening in one side thereof in alignment with a portion of the opening in the 20 cover sheet, and folding the marginal portions of said cover sheet against other sides of said frame structure to bring the remainder of the opening in said cover sheet and the portion of the transparent sheet closing the same into a position extending across and closing the opening in the 25 other side of said frame structure.

7. A method of forming a cover of a display receptacle, comprising placing upon the inner face of a cover sheet having adhesive material 30 thereon and provided with an opening a transparent sheet in position to close said opening and with its edges spaced inwardly from the edges of said cover sheet, superimposing upon said transparent sheet a frame structure having side 35 walls and a window opening in two of its adjacent walls with at least part of said opening in the frame structure in substantially aligned relation to at least part of the opening in the cover sheet and with portions of the walls of said frame 40 structure in overlying engagement with portions of the cover sheet having the adhesive material thereon, and folding the marginal portions of said cover sheet into position upon a plurality of the walls of the frame structure and uniting said marginal portions with said walls by means of said adhesive material, said cover sheet being folded in such manner that the portion of said transparent sheet which extends across the opening in said cover sheet will extend across said window opening on two walls of said frame structure and will have a rounded corner between said two walls.

8. The method of forming a cover of a display receptacle, comprising placing upon the inner face of a cover sheet having adhesive material thereon and provided with an opening a transparent sheet in position to close said opening and with its edges spaced inwardly from the edges of said cover sheet, superimposing upon said transparent sheet a frame structure having side walls and a window opening formed by two contiguous openings in adjacent walls with at least part of said opening in the frame structure in substantially aligned relation to at least part of the opening in the cover sheet and with portions of the walls of said frame structure in overlying engagement with portions of the cover sheet having the adhesive material thereon, and folding the marginal portions of said cover sheet into position upon a plurality of the walls of the frame structure and uniting said marginal portions with said walls by means of said adhesive material, said cover sheet being folded so that the transparent sheet extends across the window opening in said frame structure.

9. The method of forming a cover of a display receptacle, comprising advancing a cover sheet having an opening therein, placing a transparent sheet on said cover sheet during advancement thereof to close said opening, superimposing a 5 frame structure having side walls and a window opening formed by two openings contiguous to each other in adjacent walls upon said transparent sheet during continued advancement of said cover sheet, employing means to fold the 10 marginal portions of said cover sheet into position upon a plurality of the walls of said frame structure and uniting said marginal portions with said walls.

10. The method of forming a portion of a display receptacle which includes the steps of forming a substantially rigid paperboard frame structure having a plurality of walls connected to each other and having window openings in two adjacent walls, forming a cover sheet with a window opening corresponding approximately to said window openings in said frame structure, applying a transparent sheet to said cover sheet to extend across the window opening therein, with the edges of the transparent sheet overlapping the margins of said cover sheet around said opening, bringing said cover sheet and transparent sheet together against one wall of said frame structure having a window opening therein in such relation that said window opening in said wall is approximately registered with a portion of the window opening in the cover sheet, and folding other portions of said cover sheet against other walls of said frame structure in such manner that another portion of said window opening in said cover sheet is approximately registered with a window opening in another wall of said frame structure.

11. The method of forming a portion of a display receptacle which includes the steps of forming a substantially rigid paperboard frame structure having a plurality of walls connected to each other and having window openings in two adjacent walls, forming a cover sheet with a window opening corresponding approximately to said window openings in said frame structure, applying adhesive to substantially the whole of one surface of said cover sheet, applying a transparent sheet to the adhesive coated surface of said cover sheet to extend across the window opening therein with the edges of the transparent sheet overlapping the margins of said cover sheet around said opening to contact with the adhesive thereon and with said edges of the transparent sheet spaced materially inwardly from a plurality of edges of the cover sheet to leave a substantial portion of the adhesive coating on said cover sheet uncovered by said transparent sheet, applying said cover sheet and transparent sheet together to one wall of said frame structure having a window opening therein in such relation that said window opening is approximately registered with a portion of the window opening in the cover sheet and a portion of said wall comes into contact with an adhesive coated portion of said cover sheet, and folding other portions of said cover sheet against other walls of said frame structure in such manner that other adhesive coated portions of said cover sheet come into contact with said other walls and that another portion of said window opening in said cover sheet is approximately registered with a window opening in another wall of said frame structure.

12. A method of forming a section of a set-up

- box with a viewing window therein, which comprises forming a box section of cardboard stock with a wall and with sides permanently erected in positions substantially perpendicular to the wall, said sides being rigid with the wall, said wall and at least one of the sides having openings formed therein which are at least partly continuations of each other, forming a wrapper sheet of such size that it will cover at least the wall and extend over the sides and with an opening at least no larger than the size of the combined openings in the side and wall, applying adhesive to one face of the wrapper sheet, applying a sheet of transparent material to the adhesive coated face of said sheet to extend across said opening and to overlap a portion of said wrapper sheet around said opening in contact with the adhesive thereon, bringing the opening in the wrapper sheet into cooperative relation with the combined opening in the box section and wrapping the wrapper sheet around the box section so as to apply the wrapper sheet adhesively to the sides of the box section, the wrapping operation being carried out in such manner that the box section serves as a form about which the wrapper sheet is drawn so as to maintain the transparent sheet approximately taut and without sagging with respect to the side and wall of the box.
13. The method of forming a section of a set-up box with a viewing window therein, which

comprises forming a box section of cardboard stock with a wall and with sides permanently erected in positions substantially perpendicular to the wall, said sides being rigid with the wall, said wall, having most of its area cut away and at least one of the sides having a portion of its area cut away with the two cut-away areas being at least partly continuations of each other, forming a wrapper sheet of such size that it will cover at least the wall and extend over the sides and with an opening at least no larger than the size of the combined openings in the side and wall, applying adhesive to one face of the wrapper sheet, applying a sheet of transparent material to the adhesive coated face of said sheet to extend across said opening and overlap a portion of said wrapper sheet around said opening in contact with the adhesive thereon, bringing the opening in the wrapper sheet into cooperative relation with the combined opening in the box section and wrapping the wrapper sheet around the box section so as to apply the wrapper sheet adhesively to the sides of the box section, the wrapping operation being carried out in such manner that the box section serves as a form about which the transparent sheet and wrapper are drawn so that the transparent sheet is spanned across both of the cut-away parts without appreciable sagging.

REGINALD A. NAGLE. 30
